(57) **CLAIM**

The ornamental design for a stabilizer ring for a parachute sea anchor, as shown and described.

DESCRIPTION

FIG. 1 is a side elevational view showing a stabilizer ring for a parachute sea anchor which forms our new design, the boat, parachute and tether lines which are shown in phantom being for illustrative purposes only and forming no part of the claimed design;

FIG. 2 is a top plan view of our stabilizer ring;

FIG. 3 is a right side elevational view thereof, this view and the opposite side elevational view being mirror images;

FIG. 4 is a front elevational view thereof, this view and the opposite rear elevational view being mirror images; and,

FIG. 5 is a bottom plan view thereof.
